UNITED STATES PATENT OFFICE.

HENRY K. PORTER, OF BROOKLINE, MASSACHUSETTS.

DESIGN FOR A CUTTING-TOOL.

50,029.

Specification for Design.

Patented Dec. 12, 1916.

Application filed July 13, 1916. Serial No. 109,193. Term of patent 14 years.

To all whom it may concern:

Be it known that I, HENRY K. PORTER, a citizen of the United States, residing at Brookline, in the county of Norfolk and State of Massachusetts, have invented a new, original, and ornamental Design for Cutting-Tools, of which the following is a specification, reference being had to the accompanying drawings, forming a part thereof.

Referring to the drawings: Figure 1 is a

plan view of a pair of cutting tools, showing my new design. Fig. 2 is an edge view of the same.

I claim:

The ornamental design for a cutting tool as shown.

HENRY K. PORTER.

Witnesses:

CHARLES S. GOODING,
SYDNEY E. TAFT.
